UNITED STATES PATENT OFFICE.

MOSES E. COLLINS, OF BRIGHTON, INDIANA.

COMBINED LOCK AND LATCH.

SPECIFICATION forming part of Letters Patent No. 655,199, dated August 7, 1900.

Application filed January 3, 1900, Serial No. 249. (No model.)

To all whom it may concern:

Be it known that I, MOSES E. COLLINS, a citizen of the United States, residing at Brighton, in the county of La Grange and State of Indiana, have invented a new and useful Combined Lock and Latch, of which the following is a specification.

This invention relates to combined locks and latches, and has for its object to provide an improved device of this character in which all springs are dispensed with, the parts thereof are reduced to a minimum, and the latch is automatically operated by gravity, so as to be shot outwardly when the door-knob is released. It is furthermore designed to provide an improved locking-bolt which is securely held at its opposite limits and at the same time may be readily released and moved longitudinally by a single operation of a key.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is an elevation of a combined lock and latch constructed in accordance with the present invention, one of the face-plates of the casing being removed so as to disclose the operating parts thereof and in their locked positions. Fig. 2 is a similar view showing the lock and latch entirely withdrawn from the casing. Fig. 3 is a plan sectional view taken immediately above the locking-bolt. Fig. 4 is a detail perspective view of the locking-bolt. Fig. 5 is a detail sectional view on the line 5 5 of Fig. 1. Fig. 6 is a detail sectional view on the line 6 6 of Fig. 1.

Corresponding parts in the several figures of the drawings are designated by like characters of reference.

Referring to the accompanying drawings, 1 designates the casing, within which are housed the operating parts of the lock and latch. Located about centrally of the casing

is a substantially U-shaped latch, which is disposed so that its upper and lower arms are alined vertically and extend in substantially horizontal directions. The latch is pivotally mounted upon a suitable pivot-pin 3, which is carried by one of the face-plates of the casing and extends through the upper arm of the latch at a point nearer the outer end of the arm than the inner end thereof, whereby the latch normally hangs in a slightly upwardly inclined position. The outer free extremity 4 of the lower arm of the latch forms the latch proper for engagement with a suitable keeper and normally projects outwardly through a slot or opening 5, formed in the adjacent edge of the casing. This gravity-latch is designed to be operated by means of the rod or bolt which connects the opposite door-knobs in the usual manner, and said bolt is provided with a radially-disposed trip-lever 6, which has a circular hub 7 located at one end of the lever and projecting at opposite sides thereof, the opposite ends of said hub having bearings in suitable openings provided in the respective face-plates of the casing. A link 8 provides an operative connection between the trip-lever and the gravity-latch, one end of said link being pivotally connected to the outer free end of the upper or pivotally-mounted latch member, as indicated at 9, and the opposite lower end of said link having a pivotal connection with the outer free end of the trip-lever 6. The hub of the trip-lever is provided with an angular opening 11 for the reception of the similarly-shaped door-knob bolt, so that when turning the latter to the right the horizontally-disposed trip-lever 6 will be drawn downwardly and through the link connection 8 will also move the outer free end of the pivotally-mounted latch member downwardly, thereby swinging the entire latch member upon the pivot-pin 3 and withdrawing the latch 4 into the casing, as indicated in Fig. 2 of the drawings. Immediately upon the release of the door-knob the gravity-latch 2 will automatically resume its former position, with the latch 4 projecting outwardly beyond the casing, so as to be in position for engagement with a keeper. As indicated in Fig. 5 of the drawings, it will be seen that one side of the latch 4 is beveled, as indicated

at 12, so that the latch may be automatically forced into the casing by contact with the keeper in the usual manner.

By reference to Fig. 1 of the drawings it will be seen that the hub of the trip-lever 6 is located between the opposite arms of the latch member, so that the transverse portion thereof engages against said hub in the normal position of the latch, whereby the hub forms a stop to limit the outward movement of the latch. Moreover, the inner end of the U-shaped latch member engages against the adjacent edge of the casing in the released position of the latch, so that the edge of the casing forms a stop to limit the inward movement of the latch, and thus stops are conveniently provided for limiting the movement of the latch in opposite directions.

Located immediately below the gravity-latch and in the same vertical plane with the latter is a longitudinally-slidable locking-bolt 13, the outer end of which is designed to project outwardly through a slot or opening 14, formed in the adjacent edge of the casing.

As shown in Fig. 4 of the drawings, the upper edge of the bolt is provided with a pair of notches or recesses 15 and 16, and projecting laterally outward from the bottom of the outer notch 16 is a stop shoulder or lug 17. The rear end of the bolt is elevated somewhat above the forward end thereof, so as to form a tailpiece 18, and in the under side of the latter there is provided a substantially-semicircular opening 19, and in the upper wall of the latter there is provided an angular notch or recess 20, which is located substantially midway between the opposite sides of the semicircular opening and extends transversely of the bolt. This locking-bolt is slidably supported upon a block 21, located within the casing, or it may be supported upon the lower end of the casing, as desired. Located in rear of this locking-bolt is a block or shoulder 22, which limits the inward movement of the bolt, and pivotally connected to one side of the shoulder is a gravity-detent 23, which is located longitudinally at one side of the locking-bolt and is provided at its free end with a transverse lug or shoulder 24, forming a catch for engagement with either of the sockets or recesses 15 and 16 in the locking-bolt. Located immediately above the tailpiece 18 is a transverse pin 25, carried by one side of the casing and designed to guide the locking-bolt in its longitudinal movement and to prevent upward displacement of the bolt.

To operate the locking-bolt, a suitable key is introduced through the keyhole-slot 26, formed in either side of the casing, and the key is then turned axially, so as to engage the notch 20 in the under side of the bolt, whereby the latter may be moved longitudinally, as will be understood. As clearly illustrated in Fig. 1 of the drawings, it will be seen that the detent 23 extends below the lower open end of the notch 20, so that the key en-

gages said detent and elevates the latter out of engagement with either of the notches 15 and 16 prior to the engagement of the key with the bolt, so that the latter is free to be moved when the key has been engaged with the notch 20. Moreover, the walls of the latter flare outwardly and downwardly, so that the key may not bind within the notch. It will now be apparent that the guide and stop-pin 25 is designed to prevent the rear end of the bolt from being displaced upwardly by the engagement of the key with the notch 20, and also that the stop-shoulder 17 engages against the adjacent edge of the casing, so as to limit the outward movement of the bolt.

By reference to Fig. 6 of the drawings it will be seen that the latch projects beyond one side of the locking-bolt and in the path of the upward movement of the detent 23, so as to engage the latter and form a stop to limit the upward movement thereof, and thereby prevents accidental displacement of the detent.

As indicated by the dotted line in Fig. 1 of the drawings, the free end of the pivoted portion of the gravity-latch is also beveled upon the same side as the opposite end of the latch, and the latter is provided with a perforation 27, and the latch is designed to be removed from the pivot-pin 3 and inverted, so that the perforation 27 may receive the pivot-pin, whereby the position of the arms are reversed, so as to arrange the beveled portion of the latch at either side of the device, and thus accommodate the latch to doors moving in opposite directions.

What is claimed is—

1. In a latch, the combination with a casing, of a substantially U-shaped latch having one side or arm pivoted to the casing, a trip-lever located between the sides or arms of the latch, a link connection between the lever and the free end of the pivoted side or member of the latch and operating means for the latter.

2. In a latch, the combination with a casing having a transverse pivot-pin, of a substantially U-shaped latch, having corresponding openings or perforations provided in the opposite arms or sides thereof, and for interchangeably receiving the pivot-pin, and means for rocking the latch upon its pivotal support.

3. In a latch, the combination with a casing, having a transverse pivot-pin, of a substantially U-shaped latch, having corresponding openings or perforations provided in the opposite sides or arms of the latch, and for interchangeably receiving the pivot-pin, the opposite extremities of the arms or sides being beveled upon the same side of the latch, and means for rocking the latter upon its pivotal support.

4. In a latch, the combination with a casing, of a substantially U-shaped gravity-latch, having one arm or side pivoted intermediate

of its ends and to the casing, a trip-lever located between the sides of the latch, and having a circular hub projecting at opposite sides of the lever, and mounted in opposite openings formed in respective sides of the casing, said hub being normally in engagement with the inner side of the latch and forming a stop therefor, and also provided with an angular bore, and a link connection between the free

end of the trip-lever and the free end of the 10 pivoted side of the latch.

In testimony that I claim the foregoing as my own I have hereto affixed my signature in the presence of two witnesses.

MOSES E. COLLINS.
